(57) **CLAIM**

The ornamental design for a cable coupling, as shown and described.

DESCRIPTION

FIG. 1 is a front right perspective view of a cable coupling;

FIG. 2 is a right side view thereof;

FIG. 3 is a left side view thereof;

FIG. 4 is a front elevational view thereof;

FIG. 5 is a top plan view thereof;

FIG. 6 is a bottom plan view thereof; and,

FIG. 7 is a rear elevational view thereof.

The broken lines shown represent unclaimed subject matter and form no part of the claimed design.
